DESIGN FOR PAPER

Alfred D. Williams, Montclair, N. J.

Application November 21, 1933. Serial No. 49,817

Term of patent 7 years

To all whom it may concern:

Be it known that I, ALFRED D. WILLIAMS, a citizen of the United States, residing at Montclair, New Jersey, have invented a new, original, and ornamental Design for Paper, of which the following is a specification, reference being had to the accompanying drawing, forming a part thereof.

The view is a plan of a sheet of paper showing the design.

The drawing has been lined for color and, as shown, the difference of intensity of shading represents a difference in tone of color. The particular colors are immaterial.

I claim:

The ornamental design for paper, as shown and described.

In testimony whereof I affix my signature.

ALFRED D. WILLIAMS.
